[57] CLAIM

The ornamental design for a self-propelled riding tractor, as shown.

DESCRIPTION

FIG. 1 is a left side elevation view of self-propelled riding tractor showing our new design;

FIG. 2 is a top plan view thereof;

FIG. 3 is a right side elevational view thereof;

FIG. 4 is a bottom plan view thereof;

FIG. 5 is a front elevational view thereof;

FIG. 6 is a rear elevational view thereof; and

FIG. 7 is a top, front and side perspective view thereof. The cross hatch pattern shown in FIGS. 1 and 3 is understood to repeat throughout the indicated area as shown in FIG. 7.

FIG. 2

FIG. 1

FIG. 3

FIG. 4

FIG. 5

FIG. 6

FIG. 7
